UNITED STATES PATENT OFFICE.

CLAUDE THAYER HUMPHREY, OF GRAND ISLAND, NEBRASKA.

MOISTENER FOR ENVELOPS.

1,117,387.

Specification of Letters Patent. Patented Nov. 17, 1914.

Application filed September 22, 1913. Serial No. 791,172.

To all whom it may concern:

Be it known that I, CLAUDE T. HUMPHREY, a citizen of the United States residing at Grand Island, in the county of Hall and State of Nebraska, have invented certain new and useful Improvements in Moisteners for Envelops, of which the following is a specification, reference being had to the accompanying drawings.

10 This invention relates to certain improvements in moisteners for envelops and the object of the invention is to provide a device of this general character having novel and improved means whereby an envelop 15 to be sealed may be readily and conveniently moistened without the necessity of adjusting the closing flap from its original position.

The invention consists in the details of 20 construction and in the combination and arrangement of the several parts whereby certain important advantages are attained and the device is rendered simpler, less expensive and otherwise more convenient and 25 advantageous for use, all as will be herein-after more fully set forth.

The novel features of the invention will be carefully defined in the appended claim.

In order that my invention may be the 30 better understood, I will now proceed to describe the same with reference to the accompanying drawings, wherein—

Figure 1 is a view in top plan of a moistener constructed in accordance with my invention, the envelop and the co-acting hand being shown in dotted lines; Fig. 2 is a view in top plan of the device, as shown in Fig. 1; Fig. 3 is a central horizontal sectional view taken through Fig. 1; Fig. 4 is a sectional view taken on the line 4—4 of Fig. 1; Fig. 5 is a sectional view taken on the line 5—5 of Fig. 1; Fig. 6 is a sectional view taken on the line 6—6 of Fig. 1; Fig. 7 is a sectional view taken on the line 7—7 of Fig. 2; Fig. 8 is a horizontal sectional view taken through the supporting plate and the adjacent parts, as herein set forth, illustrating certain details of construction; and Fig. 9 is a view, detached, 50 of the clamping member, herein employed, in connection with a moistener pad.

As disclosed in the accompanying drawings, 1 denotes an elongated body preferably rectangular in form and produced of 55 any suitable material and being afforded with an elongated chamber or well 2 adapt-

ed to contain a supply of fluid. While this chamber may be positioned as desired, I prefer that it be substantially central of the body 1 so that such body will possess 60 sufficient strength to prevent it from becoming easily broken during use or from any other cause.

The chamber 2 has a side of one of its end portions laterally enlarged, as at 3, and in 65 communication with such enlarged portion 3 is the downwardly directed open ended wick slot 4 herein shown as produced in a longitudinal marginal portion of the body 1.

In alignment with the wick slot 4 and 70 disposed transversely of the body and preferably formed integrally therewith is a plate 5 having the major portion of its under face spaced from the adjacent surface of the body 1 and disposed parallel thereto and thereby affording a passage-way 6 through which the flap of the envelop to be sealed may pass thereby avoiding the necessity of adjusting such flap into an outwardly directed position relatively to the 75 body of the envelop as is compulsory in devices of this general character.

The upper surface of the plate 5 is disposed on a downwardly directed incline toward its free end and this upper surface of 80 the plate is adapted to have rested thereon the moistener pad 7 provided with an extended portion or wick 8 adapted to project through the slot 4 whereby the pad 7 may be maintained moistened or saturated by the 85 fluid within the chamber 2 through capillary attraction, as is believed to be obvious to those skilled in the art to which my present invention appertains.

The pad 7 is adapted to be removably 90 held to the upper surface of the plate 5 and for this purpose I prefer to have the free edge portions of such plate grooved, as at 9, which grooved portion is overlapped by the marginal portions of the pad 7, such 100 marginal portions being forced within the groove 9 through the medium of the spring clamping member 10 formed of non-corrosive material in a manner as is believed to be clearly apparent from the drawings.

By having the structure whereby the flap is caused to undertravel the plate 5, it will be readily understood that after the body of the envelop is moved across the pad 7, to moisten the free marginal portion of the 110 sealing face thereof, the adjacent elongated unobstructed surface of the body 1 readily

permits requisite pressure being applied to the envelop as to cause the requisite adherence of the flap to the body. In order that the flap of the envelop may be directed beneath the plate 5 with greater facility, I prefer to have the end portion of the body 1 adjacent thereto rounded, as at 11, and over which the flap will readily and conveniently pass.

10 As it is my purpose to produce the body 1 of glass or other solid material, I find it of particular advantage to surround the marginal portions of the under surface of the body 1 with suitable yieldable material, 15 as indicated by 12, whereby the device will not mar the surface on which it may be placed and in order to maintain the body 1 against sliding movement over the support on which it may be rested, I have the free 20 faces of such strips serrated, as indicated at 14.

From the foregoing description of my improvement, it is thought to be obvious that a moistener constructed in accordance with 25 my invention is of an extremely simple and comparatively inexpensive nature and is particularly well adapted for use by reason of the convenience and facility with which the sealing operation of an envelop may be 30 effected and it is also thought to be obvious from the foregoing description that my in-

vention is susceptible of some change and modification without material departure from the principles and spirit thereof and for this reason I do not wish to be understood as limiting myself to the precise arrangement and formation of the several parts herein shown in carrying out my invention into practice except as defined by the appended claim.

I claim:

A device of the character described comprising a body having a chamber therein adapted to contain a fluid and having an open ended slot in communication with such chamber, of a plate positioned adjacent the slot and extended across the body, a lower portion of the plate being spaced from the body, a pad resting upon the plate and extending through the slot to the chamber, the portion of the pad positioned upon the plate having its marginal portions overlying the edges of the plate, and removable means for clamping such marginal portions of the pad to the edges of the plate.

In testimony whereof I hereunto affix my signature in the presence of two witnesses.

CLAUDE THAYER HUMPHREY.
